UNITED STATES PATENT OFFICE.

BLANCHE DONNELSON, OF PRATT, KANSAS, ASSIGNOR OF ONE-TENTH TO FRANK GOYEN, ONE-TENTH TO WALTER PEDIGO, ONE-TENTH TO W. B. HESS, ONE-TENTH TO J. E. HARDESTY, AND ONE-TENTH TO A. S. FARMER.

PIPE WRENCH.

Application filed August 18, 1926. Serial No. 130,068.

An object is the provision of a wrench of this character in which the stationary jaw is pivotally associated with a frame of a novel construction and in which the shank 5 of the movable jaw is slidable through said frame, a spring influenced yoke member being pivoted to the frame and straddling the carriage and engaging the outer toothed edge of the shank of the movable jaw, and whereby the movable jaw may be freely adjusted with respect to the stationary jaw, effectively held at such adjustment, and further wherein a ratchet engagement is afforded between the jaws and the object 15 engaged.

To the attainment of the above broadly stated objects and others which will present themselves as the nature of the invention is better understood, the improvement further 20 consists in certain other novel features of construction, combination, and operative association of parts, a satisfactory embodiment of which is disclosed by the accompanying drawings.

25 In the drawings:

Fig. 1 is a side elevation of a wrench in accordance with this invention,

Fig. 2 is an edge view thereof, and

30 Fig. 3 is a sectional view on the line 3—3 of Fig. 1.

The stationary jaw 1 has its outer face toothed, as at 2. The stationary jaw is arranged at an angle with respect to a handle member 3 which is integrally formed with 35 the jaw. The jaw 1 extends laterally and longitudinally beyond the handle member, and the said handle, at its juncture with the outer portion of the jaw, is widened and formed with a lug 4. Passing through an opening in the lug 4 there is a pivot 5. This pivot connects the sides 6 of the frame to the handle 3. The frame has its ends formed with rearwardly extending substantially U-shaped straps 7, and its inner edge, 45 between the straps formed with a wall 8 against which the inner edge of the handle 3 contacts. The lower corner of the frame, opposite that provided with the lower strap 7, is formed with lug enlargements through 50 which pass a headed pintle 9. This pintle between the mentioned lugs 10 of the frame has arranged thereon a roller 11. Passing through the lugs and coiled around the ends of the pintle which project beyond said

55 lugs there is a spring 12. The ends of this spring are bent and extended in the same direction to contact with the outer sides 13 of a substantially U-shaped bail 14. The outer or connecting element of the arms of the bail 14 are arranged at an inclination 60 to provide the same with what I will term an angle tooth 15.

Adapted to be passed through the U-shaped straps 7 of the frame 6 there is the shank 16 of the movable jaw 17. The outer 65 edge of this shank is toothed, as at 18, and these teeth are adapted to be engaged by the angle teeth 15 of the bail 14.

The jaw 17 is, of course, arranged over the jaw 1, and has its inner or active face 70 toothed, as at 19. The wall 8 serves as a fulcrum member for the inner edge of the handle 13 and said handle may swing upon the pivot 5 toward or away from the shank 16 of the jaw 17. By this arrangement 75 the wrench may ratchet over a round object engaged between the jaws. The shank 16 may be slid between the straps 7 and the yoke 14 to adjust the jaw 17 with respect to the jaw 1, but an outward movement of 80 the said shank will be prevented by the engagement of the teeth 15 with the teeth 18 on the said shank. A slight swinging of the jaw 17 in the direction of the jaw 16 will permit of the operator swinging the 85 bail 14 against the tension of the spring 12 so that the tooth 15 of said bail will be brought out of engagement with the teeth of the shank 16 and thereby permit of an 90 outward adjustment of the jaw 17 with respect to the jaw 1 or to release an article from between the jaws. The outward swinging of the handle 3 on the pivot 5 will be limited by the contacting engagement of the 95 said handle with the roller 11.

The simplicity and advantages of the construction will, it is thought, be perfectly apparent to those skilled in the art to which such invention relates when the foregoing description has been carefully read in connection with the accompanying drawings, and therefore a further detailed description is not believed required.

Having described the invention, I 105 claim:

A pipe wrench, including a stationary jaw having a handle integrally formed therewith, a frame comprising spaced side mem-

bers and U-shaped straps extending from the ends of the side members, said side members straddling the handle and having their outer corners pivotally secured to said handle, said side members between the straps having an inner wall and having their lower corners provided with lugs, a pivot passing through said lugs, a roller on the pivot between the lugs, a spring having coiled ends surrounding the pivot, outward of the lugs, and having a central portion which contacts with the outer edge of the handle, a substantially U-shaped yoke hav-

ing its arms connected to the pivot and the coiled ends of the springs having extensions 15 for engaging the arms of the yoke, said connecting element arranged at an angle with respect to the arms and providing a tooth, a movable jaw having a shank which is slideable through the straps for the frame, and 20 the shank of the said movable jaw having its outer end toothed for engagement with the tooth of the yoke.

In testimony whereof I affix my signature.

BLANCHE DONNELSON.
